CARTTER WEAVER, OF PITTSBURGH, PENNSYLVANIA.

COLLAR BUTTON.

Application filed November 5, 1931. Serial No. 513,066.

To all whom it may concern:

Be it known that I, CARTTER WEAVER, a citizen of the United States, residing at Pittsburgh, in the county of Allegheny and 5 State of Pennsylvania, have invented certain new and useful Improvements in Collar Buttons, of which the following is a specification.

This invention relates to shirt studs or 10 collar buttons.

The object of the present invention is to provide a collar button adapted in use to modify or vary the existing size of a shirt collar band, the button illustrated being 15 constructed and arranged particularly for use with shirts the neckbands of which are too small or a tight fit upon the wearer, and being so formed as to enable the ends of the neckband to be secured to the button and at the same time separated from 20 each other a half size or size so as to in effect let out the shirt neckband and secure expansion thereof.

A further object of the invention is to 25 provide a button of the character described in which the stud for supporting the collar ends is centrally disposed between the let out ends of the shirt neckband so that the entire assembly of shirt, neckband, collar 30 and button is symmetrically arranged and secures a good appearance. A further object of the invention is to provide an improved button of this kind which is not thick or bulky and which does not take up much 35 more room, if any, than the ordinary button.

Further objects of the invention are in part obvious and in part will appear more in detail hereinafter.

In the drawings, Fig. 1 represents a front 40 view of one embodiment of the invention as the same lies in place when worn; Fig. 2 is a side elevation from the left in Fig. 1; Fig. 3 is a sectional view on the line 3—3, Fig. 1, the collar holding stud being elevated; Fig. 4 is a section on the line 4—4, Fig. 1; Fig. 5 is a detail section on a larger scale, of the collar holding stud and its supporting member; Fig. 6 is an elevation thereof looking in the direction of 45 the arrow A, Fig. 5; Fig. 7 is a view corresponding to Fig. 1 and illustrating a modification; Fig. 8 is a plan view thereof; Fig. 9 is a view corresponding to Fig. 1 and illustrating still another modification; Fig. 10 is an elevation from the left in Fig.

9; Fig. 11 is a plan view; and Fig. 12 is a view corresponding to Fig. 4 and showing another arrangement of the parts.

In the description and claims hereafter the button will be described assuming it to 60 be in place upon the wearer, and the words "horizontal," "vertical" etc., where used should be so understood. Also, "front" means outwardly from the neckband and "back" means toward the neck.

All forms of button shown in the drawings comprise a base or body portion carrying two horizontally separated studs for receiving the separated ends of the shirt neckband. One, at least, of said studs extends toward the front. The second stud may extend toward the back but preferably, as in Fig. 1, extends toward the front. The base or body portion also supports a third stud which extends forwardly and serves 70 to receive and support the collar ends, it being understood that the collar is of normal size such as should fit a shirt of the proper size for the wearer. This forwardly extending collar receiving stud is preferably mounted upon a hooked or bent portion extending outwardly from the base toward the front and also around the edge of one of the ends of the neckband, either the upper 75 horizontal edge thereof or the vertical end edge thereof. Also, the several studs for receiving neckband ends and the collar ends may lie at different positions from the front toward the back to secure overlapping relation between the collar and shirt band and also over-lapping to a slight extent, if desirable, of the ends of the shirt band. This arrangement, embodying the features 80 before described, provides a simple inexpensive, compact button which enables the ends of the collar to be brought together centrally with relation to the ends of the shirt neckband and without producing objectionable thickness or bulkiness of the 85 assembled parts.

In the form shown in Figs. 1 to 6, inclusive, the base or body portion 1 is of generally circular form although it may be slightly oval if desired. The edge may be suitably turned or rolled, as at 2, and viewed from above the base may be slightly curved to the form of the neck, as shown in Fig. 4. On the front of the base are two studs marked 3 and 4, respectively. Stud 3 extends out directly from the base while stud 100

4 is carried by an ear 5 extending toward the front from one side edge of the base and thence parallel thereto. Consequently the two studs 3 and 4 are spaced horizontally 5 from each other around the neck-band and are also spaced horizontally from front to back, stud 4 lying further toward the front than stud 3. These two studs enter the button holes in the shirt neckband, the ends of 10 which neckband are marked *a*, *b*. Ear 5 permits the band end *a* to extend beneath the band end *b* and into the recess formed by said ear, so that the ends of the band may overlap if necessary.

15 The base or body portion also carries a third stud marked 6 which is supported by an arm 7 shown as a narrow flat plate extending downwardly from the upper edge of the button base and spaced away from the 20 front surface thereof. Consequently this arm extends over the upper edge of the shirt band. In the form shown said arm is hinged or pivoted on a horizontal rod 8 which extends between two small ears 9 25 rigidly attached to the base, this construction enabling the arm 7 and the stud 6 carried thereby to be readily elevated, as shown in Fig. 3, until the stud 6 extends back toward the neck, so as to enable the ends of 30 the shirt band to be readily buttoned over the studs 3 and 4. Stud 6 is then dropped to its position and the ends of the collar are buttoned over the same. The collar stud 6 lies centrally between studs 3 and 4 so that 35 the entire assembly is symmetrical.

When the parts are all in position on the wearer the form of collar usually maintains the stud 6 and arm 7 in their normal position shown in Fig. 1 and prevents said arm 40 from turning upwardly. However, to further prevent said arm from raising, the arm may have one edge portion, such as at 10, extending slightly beyond the edge of the head of stud 3 so as to resiliently snap in 45 behind the same and releasably lock the arm down in place. This ear 10 is used when the ends of the neckband do not materially overlap, as in Fig. 4. When the ends do overlap as in Fig. 12, a second ear 10^a may 50 be snapped under the head of stud 4. Either or both of said ears may be used, as desired. In addition, the middle portion of the rod 8 may be flattened, as 55 shown at 11, Fig. 5, to receive a resilient tongue 12 cut out from the metal of the arm 7. When said arm is raised or moved outwardly the resilient tongue 12 is flexed so that the tendency of the parts is to retain them in the position shown in Figs. 5 and 6.

60 If desired, the lower end of arm 7 may be bent outwardly, as at 7^a, to form a tongue which tends to force the lower edge of the collar forwardly and tilt its upper edge rearwardly, thereby improving the fit of the collar upon the wearer and taking all looseness 65

away from the sides of the collar so that the coat fits snugly at those points.

Figs. 7 and 8 show a modification in which the base or body portion marked 15 has two horizontally separated shirt band receiving studs marked 16, 17, the first of which extends toward the back and the second of which extends toward the front. The metal of the base or body portion is bent horizontally along one vertical edge to form a hook portion 18 which extends around an end edge of the shirt band and support the collar holding stud 19.

Figs. 9, 10, and 11 show another modification in which the base or body marked 20 has two shirt receiving studs 21, 22, one extending toward the back and the other toward the front, and a metal tongue 23 which extends over the upper horizontal edge of the shirt neckband and downwardly 25 in front of the same and carries the collar receiving stud 24.

All forms of the button shown can be made of any suitable materials and are susceptible of ornamentation in the usual manner. The studs may be of any suitable description and usually consist of a small shank with a round thin head, as illustrated, although any other form of stud may be used.

The advantages and uses of the invention will be obvious to those skilled in the art and require no detailed statement.

What I claim is:

1. A collar button provided with a plurality of studs, two for receiving the ends of a shirt band, at least one of said studs extending toward the front, and a third forwardly extending stud for receiving collar ends, said two forwardly extending 100 studs being of different lengths.

2. A collar button, having a base or body portion and provided with three studs, at least two of which extend toward the front, one of said two studs being adapted to receive the collar ends and the other one end of the shirt band, the collar receiving stud being longer than the shirt band receiving stud.

3. A collar button, comprising a base or body having horizontally separated studs for receiving the ends of the shirt band and a hooked portion carrying a collar receiving stud.

4. A collar button, comprising a base or body portion having two horizontally separated studs for receiving the ends of the shirt band, said studs extending toward the front, and means supporting a third forwardly extending stud on said base between said shirt band receiving studs for receiving collar ends.

5. A collar button, comprising a base or body portion having two horizontally separated studs for receiving the ends of the

shirt neckband, and an arm extending around an edge of the shirt neckband and supporting a collar receiving stud.

6. A collar button, comprising a base or body portion having two horizontally separated studs for receiving the ends of the shirt neckband, and an arm extending around the edge of the shirt neckband and supporting a collar receiving stud, said arm being hinged to the base or body portion and adapted to be swung outwardly therefrom.

7. A collar button, comprising a base or body portion having two horizontally separated studs for receiving the ends of the shirt neckband, and an arm extending around the edge of the shirt neckband and supporting a collar receiving stud, said arm being hinged to the base or body portion and adapted to be swung outwardly therefrom, and means for releasably holding said arm in place.

8. A collar button, comprising a base or body portion, three studs one for receiving the collar ends and one for each of the shirt band ends, and means extending around an edge of the shirt band for supporting one of said studs.

9. A collar button, comprising a base or body portion, a plurality of studs carried thereby for receiving the collar and shirt band ends, and means extending around an

edge of the shirt band for supporting two of said studs, one of which receives a shirt band end and the other of which receives the collar ends.

10. A collar button, comprising a base or body portion, two arms thereon, one extending around a vertical end edge of the shirt band, and a stud carried by each of said arms.

11. A collar button, comprising a base or body portion carrying a rigid stud, a rigid arm on said base extending around an edge of the shirt band and carrying a second stud, and a movable arm on said base carrying a collar receiving stud.

12. A collar button, comprising a base or body portion carrying a rigid stud, a rigid arm on said base extending around an edge of the shirt band and carrying a second stud, and a second arm extending around an edge of the third band and carrying a shirt stud.

13. A collar button, comprising a base or body portion carrying a rigid stud, a rigid arm on said base extending around an edge of the shirt band and carrying a second stud, and a pivoted arm extending around an edge of the shirt band and carrying a third stud.

In testimony whereof I hereby affix my signature.

CARTTER WEAVER.
